DESIGN FOR A BOTTLE

James Mandes, Washington, D. C.

Application July 23, 1934, Serial No. 52,675

Term of patent 3½ years

To all whom it may concern:

Be it known that I, JAMES MANDES, a citizen of Greece, and a resident of Washington, District of Columbia, have invented a new, original, and ornamental Design for a Bottle, of which the following is a specification, reference being had to the accompanying drawing, forming part thereof.

Figure 1 is a front elevational view of the bottle, showing my new design.

Figure 2 is a side elevational view of the bottle.

I claim:

The ornamental design for a bottle, as shown.

JAMES MANDES.
